CENTRIFUGALLY OPERATED MERCURY SWITCH

Joseph H. Staley, Columbus, Ind.

Application December 16, 1939, Serial No. 309,524

8 Claims. (Cl. 200—80)

This invention relates to a mercury switch of the type having a quantity of mercury flowable between two parts of a metallic envelope. The invention herein relates specifically to a switch structure particularly adapted for centrifugal operation wherein the closing and opening of an electrical circuit is produced by the change in shape of a globule of mercury under centrifugal action rather than by a flow bodily of the entire mass of mercury from one part of the envelope to another.

One particular advantage of the present invention is the high degree of sensitivity obtained. Another important advantage is that there is but a small number of intervening revolutions between the closing and opening of the circuit.

These and other important advantages of the invention will become apparent to those versed in the art in the following description of one particular form of the invention as illustrated in the accompanying drawing, in which

Fig. 1 is a central transverse section through a structure to which the invention is applied;

Fig. 2, a section on the line 2—2 in Fig. 1;

Fig. 3, a longitudinal diametrical section through a switch embodying the invention; and

Fig. 4, a transverse section on the line 4—4 in Fig. 3.

Like characters of reference indicate like parts throughout the several views in the drawing.

Referring first to Fig. 3 of the drawing, an envelope is formed out of any suitable material, such as iron, to consist essentially of a tubular body 10 integrally closed at one end and open at the other and having an exterior portion adjacent the open end reduced in diameter preferably from that of the remainder of the tube to receive thereover an insulating sleeve 11 to be telescopically engaged by a cap 12 likewise made out of iron. The sleeve 11 is made out of any suitable resilient insulating material and is compressibly engaged between the body 10 and the cap 12 with sufficient frictional engagement so as to firmly retain the cap 12 in position thereover against considerable internal pressure. In the form herein shown, the sleeve 11 is in two lengths separated by an intervening elastic seal 13 as shown and described in my Patent No. 2,045,003, issued June 23, 1936.

In the outer end of the sleeve 11 which is made to extend beyond the open end of the body 10 is frictionally engaged a ceramic annulus 14 hereinafter termed a breaker. This breaker 14 is firmly gripped by the resilient sleeve 11 by the cap 12 thereover so that the breaker is fixed in

10 longitudinal position in respect to the various elements. The breaker 14 may have a slight clearance left between it and the end of the body 10, as indicated in Fig. 3, or it may be abutted thereagainst as indicated in Fig. 1. Preferably the clearance is provided in order to thoroughly insulate the breaker 14 against externally produced shocks such as would be set up by dropping the switch or the like. The breaker 14 is, in any event, of insulating material of a character resisting deterioration in the presence of electric arcs that may be produced upon the making and breaking of a circuit thereover, and is particularly provided to protect the resilient fiber sealing sleeve 11.

15 To the cap 12 is secured in any suitable manner an axially positioned electrode 15 in the nature of a rod, to have a length carrying it well within the body 10 to terminate near the closed end thereof. This rod 15 is preferably made out of iron and may be secured by welding it to the inside of the cap 12 or by boring a hole through the cap 12, as suggested in Fig. 3, and then welding to insure not only a fixed position but also a gas tight seal therearound through the cap. The diameter of this rod 15 is such that it fills the major proportion of the cross-sectional area of the central bore through the breaker 14 thereby leaving an annular opening therearound of limited area, as indicated in Fig. 4.

20 A quantity of mercury 16 is placed within the body 10 before the cap 12 is forced thereover in the sealing operation and as is the usual practice, the atmospheric gases are evaporated and 25 replaced by some gas such as hydrogen. The quantity of mercury 16 employed is just sufficient to fill in that part of the cap 12 beyond the breaker 14, the annular chamber in the breaker about the rod 15 and to come in contact for a short 30 distance with the open end of the body 10 when the cap 12 is turned downwardly as indicated in both Figs. 1 and 3. The area of contact of the mercury 16 with the body 10 above the breaker 14 is made to be sufficient to carry the desired 35 amount of current for which the switch is rated without causing undue heating arising from resistance.

40 This type of switch is intended to be operated by revolving the switch bodily around an axis of revolution to have the axis of the switch fixed permanently parallel with that axis of revolution.

45 One particular mechanism for so mounting and whirling the switch is indicated in Figs. 1 and 2 wherein the switch structure above described carries terminal bands 17 and 18 about

the respective body and cap ends to have the ends of these bands secured one over the other to an insulating block 19 which in turn is secured to a metallic post 20. This metallic post 20 is fixed to a base 21 that is revolved in any suitable manner by a shaft 22 connecting therewith, such as by screw-threads, with a post 23 extending therefrom. The shaft 22 is, of course, revolved at the rate of speed in accordance with or in proportion to the speed of the member to be controlled. From the terminal clips 17 and 18 lead terminal wires 24 and 25 to conductor rings 26 and 27 respectively insulatedly carried about the post 23. Suitable brushes 28 and 29 bear against the respective rings 26 and 27 in order to provide circuit connections therewith and hence with the body and cap ends of the switch. The brushes 28 and 29 are, of course, held in fixed positions relative to the turning of the post 23.

Depending upon the size and proportions of the switch parts, the mercury 16 therein will remain in contact with both the body 10 and the rod 15 up and through predetermined speeds of revolution of the switch. Above such speeds, the mercury 16 will tend to overcome its skin effect or cohesion normally tending to hold it in a spherical shape and flatten out against that side of the switch furthest removed from the axis of revolution to assume some such shape as suggested in Fig. 3 where there will be a thin sheet of mercury above the breaker 14 pressed by centrifugal action against the body 10 with possibly a lesser amount down below the breaker 14 in the well thereunder in the cap 12, the original body of mercury having separated into these two bodies with the line of division occurring substantially at the stop of the breaker 14 where the arc would be entirely cut off by the mercury above and below that divisional zone. Primarily the circuit interruption occurs between the mercury and the rod 15 above the breaker 14. Thus in this condition, the mercury has so positioned itself under the effect of centrifugal action as to have interrupted the circuit between the body 10 and the rod 15 by this "flattening" action. The body 10 does not tilt but remains fixed in parallel alignment as above indicated with the axis of revolution.

This circuit interruption may be employed, of course, in a conceivably wide range of methods of speed control, the particular methods not entering per se into the present invention. As soon as the speed has dropped following the circuit interruption sufficiently to permit the gravitational effect and inherent cohesion to operate on the mercury, the mercury will re-assume its unitary condition to reestablish the circuit between the body 10 through the breaker 14 with the cap 12. It is to be noted that any arcs produced upon either the making or breaking of the circuit must occur immediately adjacent or within the breaker 14 to be essentially surrounded initially by masses of mercury.

The switch above described functions admirably in combination with a tilting switch 30 mounted to operate in the manner indicated and shown in my pending application for patent, Serial No. 143,087, particularly in respect to Fig. 3 thereof. This switch 30 is pivotally mounted by the pin 31 on the insulating block 32 fixed to the base 21 so that its upper end may swing outwardly from the axis of revolution under the effect of centrifugal action subject to the pull

of the restraining spring 33 which, in the present form, is shown as being interconnected between the terminal clip 34 about the body end of the switch 30 and an ear on the upper end of the post 20.

The switch 30, in the present form, is shown as having a cap 35 telescoping over an insulating sleeve 36 to carry it compressibly against the exterior part adjacent the open end of the body part of the switch 30 and a ceramic breaker 37 is positioned between the end of the body and the cap as indicated to leave an opening through the breaker 37 substantially equal in diameter to the interior diameter of the body of the switch. A mass of mercury 38 is carried within the switch and this mass flows up and down the wall of the switch as it is inclined from and returns toward the vertical position as the speed may vary in whirling the switch around the axis of rotation. The terminals from this switch 30 likewise lead to the contacting rings 26 and 27 in order to provide connections for the controlling circuit.

In reference to the use of the invention, a wide range of controls may be effected. For example, one switch may be connected into a circuit to provide a closed circuit at certain speeds and the other switch will be so connected as to open that circuit upon a predetermined speed being reached thereabove. The particular advantage in the use of the two types of switches is that the one centrifugal control device may be used in not only starting an electric device, such as a motor, but also in controlling its speed within predetermined limits, one switch controlling a part of the range of speeds and the other switch controlling another range. Those versed in the art will readily appreciate the further advantages of the use of this particular combination.

While the invention has herein been shown in the one particular form, it is obvious that structural variations therefrom may be employed without departing from the spirit of the invention and it is, therefore, desired that the invention not be limited to that precise form beyond the limitations as may be imposed by the following claims.

The invention claimed is:

1. A mercury tube switch for centrifugal operation comprising a constant diameter tubular metallic envelope; a rod-like electrode insulatedly supported by the envelope and extending axially into and along substantially the entire length of the envelope; a ceramic breaker formed as an annulus to surround said electrode; said breaker being located at one end of the envelope; means for revolving the switch; means mounting the switch with its axis fixed substantially parallel to and eccentrically of the axis of revolution of said revolving means; and a limited quantity of mercury in said envelope; whereby said mercury may tend to form a globular mass at any position along said envelope beyond said breaker and normally be in contact with said electrode to complete a circuit between the electrode and the envelope, and upon revolution of the switch bodily with axis parallel to the axis of revolution, said mass will flatten and withdraw from said electrode contact.

2. A mercury tube switch for centrifugal operation comprising a constant diameter tubular metallic envelope; a rod-like electrode insulatedly supported by the envelope and extending axially into and along substantially the entire

length of the envelope; a ceramic breaker formed as an annulus to surround said electrode; said breaker being located at one end of the envelope; means for revolving the switch; means mounting the switch with its axis fixed substantially parallel to and eccentrically of the axis of revolution of said revolving means; and a limited quantity of mercury in said envelope; whereby said mercury may tend to form a globular mass at any position along said envelope beyond said breaker and normally be in contact with said electrode to complete a circuit between the electrode and the envelope, and upon revolution of the switch bodily with axis parallel to the axis of revolution, said mass will flatten and withdraw from said electrode contact; a metallic closure across an end of the envelope and insulated therefrom; and said electrode being fixed to said closure.

3. A mercury tube switch for centrifugal operation comprising a tubular metallic envelope; a rod-like electrode insulatedly supported by the envelope and extending axially into and along substantially the entire length of the envelope; a ceramic breaker formed as an annulus to surround said electrode; said breaker being located at one end of the envelope; means for revolving the switch; means mounting the switch with its axis fixed substantially parallel to and eccentrically of the axis of revolution of said revolving means; and a limited quantity of mercury in said envelope; whereby said mercury upon revolution of the switch may tend to form a globular mass at any position along said envelope beyond said breaker and normally be in contact with said electrode to complete a circuit between the electrode and the envelope, and upon further revolution of the switch, said mass will flatten and withdraw from said electrode contact; a metallic closure across the lower end of the envelope and insulated therefrom; and said electrode being fixed to said closure; and said breaker being radially spaced from said electrode to provide a mercury passage therealong.

4. A mercury tube switch for centrifugal operation comprising a sealed, tubular, metallic envelope; a rod-like electrode insulated and supported from the envelope extending axially into and substantially throughout the entire length of the envelope; means for revolving the switch; means mounting the switch with its axis fixed substantially parallel to and eccentrically of the axis of revolution of said revolving means; and mercury in the envelope limited in quantity to form normally a localized mass in any position along the envelope tending to assume a globular form sufficient in depth to contact both the envelope and the electrode; whereby upon bodily revolution of the switch may cause at a critical speed a flattening of the mercury mass to break said contact; a closure cap across the lower end

5 of the envelope to which cap said electrode is secured; means insulating the cap from the envelope; and a ceramic annulus between the cap and the envelope and axially surrounding the electrode in spaced relation to permit passage of the mercury along the electrode through the annulus.

5. A centrifugal control comprising a rotary part; a tubular mercury switch mounted on the part to have its axis substantially parallel to the axis of revolution of said part; an electrode extending axially within the switch; and mercury in the switch limited in quantity normally to contact said electrode and to flatten at a critical

10 speed of said part away from contact with said electrode; and a second mercury switch bodily shiftable on said part under impulse of centrifugal force between positions making and breaking an associated electrical circuit, said second switch being biased to one of said positions; the mercury in the first switch controlling the associated circuit by change in shape, and the mercury of the second switch controlling the circuit by change in position.

15 6. A centrifugal control comprising a rotary part; a mercury tube switch pivoted on the part in offset relation to the part axis to rock under the effect of centrifugal force and thereby variably position its mass of mercury relative to at least one of the electrodes of the switch; means biasing the switch toward said axis; a counterbalance member fixed in position on said part in opposing diametrical relation to the switch; said counterbalance including a fixed positioned 20 mercury tube switch axially aligned with said axis, an axial electrode therein, and a mass of mercury normally in contact with that electrode changing shape under centrifugal force to break said contact.

25 7. A centrifugal control comprising a rotary part; one mercury switch mounted on the part to swing bodily under centrifugal force to control an associated circuit by shift in position of the mercury in the switch; and a second mercury switch mounted in fixed position on said part to have the mass of mercury therein change its shape under centrifugal force to modify control of said circuit.

30 8. A centrifugal control comprising a rotary part; one mercury switch mounted on the part to swing bodily under centrifugal force to control an associated circuit by shift in position of the mercury in the switch; and a second mercury switch mounted in fixed position on said part to have the mass of mercury therein change its shape under centrifugal force to modify control of said circuit; said switches being arranged in substantial counterbalance; and spring means opposing centrifugal force on said swinging switch.

JOSEPH H. STALEY.
